US0D1096823S

(12) **United States Design Patent** (10) **Patent No.:** **US D1,096,823 S**
Zavakos et al. (45) **Date of Patent:** **** Oct. 7, 2025**

(54) **DISPLAY SCREEN OR PORTION THEREOF WITH GRAPHICAL USER INTERFACE**

(71) Applicant: **Salesforce, Inc.**, San Francisco, CA (US)

(72) Inventors: **Bradly Zavakos**, Indianapolis, IN (US); **Eric Paul Wittke**, San Francisco, CA (US)

(73) Assignee: **Salesforce, Inc.**, San Francisco, CA (US)

(**) Term: **15 Years**

(21) Appl. No.: **29/867,380**

(22) Filed: **Oct. 21, 2022**

Related U.S. Application Data

(62) Division of application No. 29/740,040, filed on Jun. 30, 2020, now Pat. No. Des. 971,242.

CLAIM

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen or portion thereof with graphical user interface showing the claimed design; and,

FIG. 2 is a front view of a second embodiment thereof. The outermost dashed broken lines show a display screen or portion thereof, and form no part of the claimed design. The remaining dashed broken showing text and portions of the graphical user interface form no part of the claimed design.

1 Claim, 2 Drawing Sheets
(1 of 2 Drawing Sheet(s) Filed in Color)
